CLAIM

The ornamental design for a dust mop head, as shown and described.

DESCRIPTION

FIG. 1 is a top plan view of a dust mop head showing my new design wherein the bows shown in broken line representation are unclaimed subject matter;

FIG. 2 is a bottom plan view thereof;

FIG. 3 is a front elevation view thereof;

FIG. 4 is a rear elevation view thereof;

FIG. 5 is a side elevation view thereof;

FIG. 6 is a side elevation view thereof, opposite the side shown in FIG. 5;

FIG. 7 is a side elevation view of a double-faced embodiment of my new design;

FIG. 8 is a front elevation view of the FIG. 7 design; and,

FIG. 9 is a rear elevation view of the FIG. 7 design. The undisclosed side of the second embodiment is substantially the same in appearance as the side shown in FIG. 7 and the undisclosed top and bottom of the second embodiment are substantially the same in appearance as the bottom of the first embodiment shown in FIG. 2. The broken lines shown across the top and down the center of the fabric head represent conventional stitching.
